POURING ATTACHMENT FOR CONTAINERS

Richard E. Deschner, Los Angeles, Calif.

Application August 4, 1941, Serial No. 405,278

11 Claims. (Cl. 215—73)

This invention relates to pouring attachments adapted for use with containers from which liquids are dispensed.

A leading object of the invention is to provide for throat portions of liquid dispensing containers, a pouring attachment seatable within such throat portion in a protruding relation thereto, said attachment being compressible to a retracted position by the application of a closure to the container, said pouring attachment when the closure is removed automatically assuming a protruding position wherein it displays a pouring lip or flange of larger diameter than the pouring portion of the throat of the container. When in said protruding position the portion of the attachment which remains within the throat of the container expands thereagainst and prevents the device from falling from the container during a pouring operation.

Another object of the invention is to provide an improved container structure consisting in part of a pouring lip structure which automatically extends itself into an operative position when the cover is removed from the container, said pouring lip structure being automatically returned to its retracted position upon application of the cover to the container.

Additional objects are; to provide an efficient pouring spout which is adapted to be used with bottles and closures made like they are in present practice; to save the user the trouble of extracting the spout at the time of unsealing the bottle and therefore to insure use of the spout at every pouring operation; and to provide a spout which automatically expands into a close fit with the bottle neck when the bottle is unsealed thereby preventing leakage between itself and the container's neck.

A still further and highly important object is to provide an automatic spout-extending means which may be included as an inherent feature in a two-part container and spout combination, thereby allowing such combination to perform its automatic spout-extending function with an absolute minimum of parts.

Aside from the foregoing specified objects and with still further objects in view, the invention resides in the novel arrangement and combination of parts and in the details of construction hereinafter described and claimed, it being understood that changes in the precise embodiments of the invention herein disclosed may be made within due scope of that which is claimed without departing from the spirit of the invention.

Referring to the drawing, wherein are shown preferred and alternate embodiments of the invention as actually used in practice.

Fig. 1 is a fragmentary cross sectional perspective of the container, closure and pouring attachment, showing the latter as it appears when the closure cap is applied and the attachment is in its inoperative, diametrically contracted position.

10 Fig. 2 is a fragmentary cross section of the container with the closure removed and with the pouring attachment extended to the operative pouring position, the pouring attachment being shown in side elevation.

15 Fig. 3 is a fragmentary perspective view of a modified form of the attachment, shown in its extended, operative position.

Fig. 4 is a perspective view, partly in section showing another modification. In this view the attachment is shown not quite fully extended.

20 One embodiment of the invention is shown in Figs. 1 and 2. In Fig. 1, the numeral 7 indicates the top portion of a bottle or other container structure and the numeral 8 indicates the pouring spout attachment sealed in its retracted position by the closure cap 9. The attachment according to the species shown in Fig. 1, may be formed from a single piece of resilient sheet material, preferably by a die, and is stamped or 25 pressed into a tubularly flared split shape consisting of a vertically disposed wall 10 and an outwardly tapered wall 11, the upper edge of the tapered wall terminating in an outwardly directed and substantially horizontal circumferential flange 12. The edges 13 and 14, where the attachment is split, over-lap as do the adjacent edges 15 and 16 of the horizontal flange 12.

30 The pouring attachment is capable of being diametrically contracted, this action resulting in its being given a resilience whereby to automatically expand itself when released.

35 In the contracted position of the attachment shown in Fig. 1, the horizontal flange 12 overlies, to a slight degree, the top edge 17 of the container; the tapered body portion 11 contacts in a substantially circumferential manner with engaging shoulder 18 of the container's mouth, and the body wall 10 occupies a position inwardly spaced from the throat wall 19 of the container's neck. The gasket 20 underlies the cap 9 and seals the attachment in this position, provided that the closure 9 is firmly applied to the container 7.

40 In Fig. 1 it will be noted the degree of overlap of the edges 13, 14, 15, and 16, is much greater

than that shown in Fig. 2. In Fig. 2 the closure 9 has been removed and consequently the resiliency of the spout, in causing an increase in its own diameter, has automatically lifted said spout up to its pouring position where its pouring edge is well spaced above the mouth of the container. This lifting was due to the action of the tapered wall 11 against the engaging shoulder 18 and is facilitated by a low coefficient of friction between these parts. There is enough resiliency still left in the spout attachment when automatically extended to the position shown in Fig. 2, to cause a frictional fit between the cylindrical portion of the wall 10 and the container's neck 7 so that when the container is canted the spout will not fall out.

The lip or flange 12 serves the double purpose of promoting dripless pouring and of giving the spout a flat bearing surface against the closure gasket 20, rather than a sharp edge, so that the spout will not cut into or mar the gasket as the closure 8 is being screwed down onto the container and the attachment is undergoing a change in diametrical contraction. As a further precaution against defacing the gasket, the radial edge of the overlapping flange 16 is chamfered as indicated by the numeral 21.

In the modified form shown in Fig. 3 the pouring spout attachment 25 is constructed with an open side rather than with an overlapping joint. The parts shown possess the same generic, spout-lifting characteristics as the combination of parts 7 and 8 in Fig. 1. Spout 25 is well adapted to be made from plastics since plastics must be molded too thick to permit of a proper lap joint. Instead of the tapered wall 26 bearing on the shoulder around the mouth of the container 27, one or more bulging ribs 28 are provided across the tapered wall 26 to take the wear. It has been found that in the presence of some food substances these ribs are helpful in preventing sticking of the spout. Also, if there is any liquid left outside the spout after a pouring operation, its return into the container is facilitated by the space between the ribs while the closure is being applied. It is to be understood the use of ribs is not to be restricted to the type of spout shown in Fig. 3, nor is the use of ribs particularly necessary to the successful operation of the type spout shown in Fig. 3.

Spout 25 is equipped with a flange 29 which is similar in construction to the flange 12 of spout 8 except that it extends for less than 360° in a circumferential direction and has its uppermost surface formed with a somewhat rounded contour. This type flange has been found to operate as an efficient bearing surface for the closure to press against as it depresses the spout, notwithstanding the discontinuous nature of said flange.

In the modification illustrated in Fig. 4, the spout 31 and container 35 are shown provided with the same generic spout-lifting features as the previous specie described. In this form, however, the tapered portion 34 is provided in the wall of container 35 and the engaging shoulder 33 is provided on the spout 31. In forming the spout-lifting means, said tapered wall 34 acts against shoulder 33 with a sliding fit in a similar manner to which the tapered walls 11 and 28 of spouts 8 and 25 act upon the engaging shoulder 18 provided on container 7 shown in Fig. 1 or similar shoulder in Fig. 3. The container neck 35 is shown with a substantially cylindrical portion 32 at its outer end thus providing the 75

spout-retaining means which, after the spout has reached its fully extended position, causes a frictional fit between said spout and the container's neck so that when the container is canted the spout will not fall out. The spout 31 is shown to have a pouring lip 36 such as is shown in the case of the other forms illustrated.

In the operation of the several forms shown in Figs. 1, 2, 3, and 4, the spout is originally inserted in a slightly stressed condition within the container neck to the approximate extent shown in Figs. 2, 3, and 4. This is the spout's pouring position, and it is characterized by the space that separates the spout's pouring edge from the container's mouth, the space being great enough to prevent liquid which has left the pouring lip during a pouring operation, from touching the container's neck. When screw threads 37 are provided on the container neck as shown, the closure 8, which is common to all specie, may be applied and screwed down thereby bringing the closure and spout to the positions shown in Fig. 1, or to a like position in case the forms shown in Figs. 3 and 4 are used.

As the closure is forced down, the lower face of its gasket 20 bears against the pouring edge 12 of the spout member, depressing said spout and causing a sliding action between the tapered wall 11 and engaging shoulder 18. This results in a diametrical contraction of the spout, the cylindrical portion of said spout withdrawing from the surrounding throat wall of the container as shown in Fig. 1. The diametrical contraction of the spout causes an additional stress to be set up in the spout due to the body deformation, enabling it to spring back out to its extended pouring position of its own accord when the closure is removed. The extension movement will cease as soon as the spout has moved outwardly to its 40 pouring position because at this point it is prevented from farther diametrical expansion by the contact between the cylindrical portions of the spout and the container neck.

The tapered surface and engaging shoulder shown as a generic feature in all forms of the invention illustrated, must be correctly proportioned with regard to the elastic range of the spout, the best pouring position of the spout, and the coefficient of friction of the spout against the container neck. In general, if the degree of taper or length of taper is too great, then the elastic range of the spout will not be sufficient to provide a final frictional fit with the container to retain the spout therein after the spout has reached its pouring position. If the incline of the taper is too slight, the spout when released will not rise of its own accord because the pressure between the taper and engaging shoulder will produce too small a lifting force to overcome the friction of the sliding surfaces.

To avoid misunderstanding of the significance of some of the words used in the claims, definitions are provided as follows:

(a) The words "break" or "split" or "slit" are used to denote the discontinuous feature of the circumferential wall of the spout which gives the spout the quality of being contractible and expansible.

(b) The words "pouring position" are intended to indicate the way the spout is disposed in relation to the container mouth when the pouring edge or mouth of the spout is extended outward from said container's mouth sufficiently far to prevent liquid which leaves the said pouring edge during a pouring operation from touching the

part of the container immediately surrounding said mouth.

(c) The words "depressed position" are intended to indicate the way the spout is disposed in relation to the container mouth when the pouring edge or mouth of the spout is in a substantially flush relation with the part of the container surrounding said mouth.

(d) The words "truncated cone," "frusto-conical," "taper," and "tapering," are used interchangeably.

What I claim is:

1. As an article of manufacture, a spout consisting of an annulus of resilient material having a substantially lengthwise break in the continuity of its wall, said spout having one end portion substantially cylindrical and its opposite end frusto-conical, said frusto-conical portion being adapted to contact with the throat portion of a bottle as said spout is moved axially into said throat portion under the urge of a closure applied to the mouth of said bottle, said frusto-conical end diametrically and circumferentially contracting whereby upon removal of said closure, to automatically eject said spout to its 25 pouring position wherein said cylindrical portion frictionally engages the wall of the throat portion thereof.

2. As an article of manufacture, a self-locating spout adapted to co-operate with a container provided with means for engaging said spout, said means being integral and stationary in relation to said container, said spout having in relation to said container a pouring position and a depressed position and being resilient and inherently shaped whereby to progressively decrease its diameter as it is forced into said container from its pouring position to its depressed position, thereby acquiring the energy to spring forth and locate itself automatically in its pouring position when released.

3. In combination with a container neck member, and a resilient, contractible spout member having a pouring edge and adaptable to being positioned within the said container neck, a spout-extruding means consisting of a tapering surface provided integral with one of the members and a shoulder portion provided integral with the other member, said tapering surface and shoulder portion being adapted to contact each other to automatically extrude the said spout from a position wherein the pouring edge of said spout is in a substantially flush relation with the container neck, to a pouring position wherein the pouring edge of said spout is in a spaced relation to the container neck.

4. In combination with a container neck member, a closure therefor and a resilient, contractible, and expandable spout member having an extended position in which there exists a pouring clearance between a mouth provided on said spout member and the said container neck member sufficient in amount to prevent poured liquid leaving the mouth of said spout from contacting the said container neck, automatic means for moving said spout member into said extended position when the said closure is removed, said automatic means consisting of a tapering portion provided integral with one of said members and a shoulder portion provided integral with the other, said tapering portion being of greater slant length than the distance forming the aforementioned pouring clearance.

5. In combination with a container neck, and a resilient, contractible spout having a pouring

edge and adaptable to being positioned within the said container neck, a spout-extruding means consisting of a tapering surface provided integral with the container neck and a shoulder portion provided integral with the spout, said tapering surface and shoulder portion being adapted to contact each other to automatically extrude the said spout from a position wherein the pouring edge of said spout is in a substantially flush relation with the container neck, to a pouring position wherein the pouring edge of said spout is in a spaced relation to the container neck.

6. As an article of manufacture, a self-extending spout for use in the mouth of a container, said spout having in relation to said container mouth a fully depressed position and a pouring position, said spout consisting of a diametrically contractible band of elastic material having the general form of a truncated cone with a substantially lengthwise break in its surface, said truncated cone portion being adapted to engage a shoulder provided on said container mouth, both in the spout's fully inserted position and its pouring position, said cone portion having formed thereon in an inclined relation thereto, a portion adapted to contact the container only when the spout is in its extended position.

7. As an article of manufacture, a pouring spout for containers consisting of an annular band of resilient material having a frusto-conical flare throughout one end portion of the spout which it forms and being substantially cylindrical throughout the remaining portion of said spout, said band having its end portions in a loose relation to form means whereby said band is circumferentially contractible, the material of the band being so stressed when said flared portion is diametrically contracted by being forced into a container by a cap applied thereto, to tend to extrude itself automatically from the container.

8. As an article of manufacture, a spout having a mouth and being made of resilient material of tubular form and split in the general direction of its length, said spout having one end portion substantially frusto-conical and its opposite end inclined in relation thereto, said frusto-conical portion being circumferentially contactable with a shoulder portion of a bottle in which said spout is adapted to be inserted and moved from a slightly stressed position wherein the mouth of said spout is in a spaced relation to the mouth of the bottle, to a highly stressed position wherein the mouth of said spout occupies a substantially flush relation with the mouth of said bottle, said frusto-conical portion moving inwardly and obliquely to the axis of the bottle across said shoulder under the urge of a closure being applied to said bottle, such inward movement of the spout diametrically and circumferentially contracting said spout.

9. The combination with a container and a closure therefor; of a spout mountable in the mouth of said container, said spout having a mouth and being automatically extrudable from a position wherein the mouth of the spout is in a substantially flush relation with the mouth of the container, to a position wherein the mouth of said spout occupies a position in an extruded spaced relation to the mouth of said container, said spout being constructed with a substantially frusto-conical portion at one end, and a portion at its opposite end inclined in relation to said frusto-conical portion, and said container being provided with an annular shoulder which said frusto-conical portion contactingly over-rides in

a direction oblique to the axis of the container as said spout is moved in opposite directions in said mouth under the control of the application or release of the closure with the container.

10. The subject matter of claim 9 and, said spout being provided with a peripheral lip around its mouth projecting outwardly and positioned to make a substantially flat-wise contact with the

inner face of said closure during application thereof to the container.

11. The subject matter of claim 9 and, said frusto-conical portion of the spout having a plurality of external bulges which extend in the general direction of the length of the spout.

RICHARD E. DESCHNER.
